UNITED STATES PATENT OFFICE.

EDWARD R. BRODTON, OF WASHINGTON, DISTRICT OF COLUMBIA, ASSIGNOR, BY MESNE ASSIGNMENTS, TO SYPHO-CHEMICAL SPRINKLER CORPORATION, OF NEW YORK, N. Y., A CORPORATION OF NEW YORK.

FIRE-EXTINGUISHER.

1,315,279.

Specification of Letters Patent.

Patented Sept. 9, 1919.

Application filed November 2, 1915. Serial No. 59,263.

To all whom it may concern:

Be it known that I, EDWARD R. BRODTON, a citizen of the United States, and resident of Washington, District of Columbia, have 5 invented a certain new and useful Improvement in Fire-Extinguishers, and do hereby declare that the following is a full, clear, and exact description thereof.

My invention relates to fire extinguishers, 10 and in certain of its features relates more particularly to automatic sprinkler systems, and in this relation my object primarily is to provide a construction in which, under some conditions, a chemical extinguisher 15 will be emitted from the open sprinkler head to the fire, and under other conditions, which render the use of a chemical objectionable, or undesirable, another kind of extinguisher, such as water, will be emitted as the extinguishing liquid. Other objects of my invention 20 and advantages of the construction that I have invented will appear when the construction and operation of the apparatus that I show in the drawings is understood.

25 In the accompanying drawings—

Figure 1 is a view somewhat diagrammatic of a system embodying one form of my invention;

Fig. 2 is a similar view of another embodiment thereof;

Fig. 3 is a detail view, partly in section of a form of apparatus that I have invented for automatically generating, or causing to be generated, the pressure required for expelling the extinguishing liquid;

Fig. 4 is a detail view in section of a form of check valve used in the system in the pipe or connection between the two extinguisher holding tanks;

Fig. 5 is a detail view of a valve form device that is adapted to cause the operation of an alarm upon the opening of a sprinkler head;

Fig. 6 is a detail view showing the cartridge form of the pressure producing reagents.

In the embodiment of my invention shown in Fig. 1, I show two extinguisher supply pipes, one designated A connected with and 50 leading from a tank or holder 10 containing a supply of some form of chemical extinguisher, such as carbon tetra chlorid, and the other pipe B being connected with and leading from a suitable source of supply of a

different kind of extinguishing fluid, either 55 water, or carbonic acid, such source of supply, as shown, being a holder, or tank 11. From the pipe A, a suitable number of branch pipes 12 provided with automatically opening sprinkler heads 13 lead to those 60 places where it is desired to use chemical extinguisher in the form of say, carbon tetra chlorid, while from the pipe B the desired number of distributing pipes 14 provided with automatic sprinkler heads 15 run to 65 those parts of the building, or structure to be protected, where water, or some other extinguisher than carbon tetra chlorid is to be used. All the pipes, including the pipes having the sprinkler heads, are filled with 70 the extinguishing fluid, and the latter is kept under a pressure tending to cause its efflux upon the opening of a sprinkler head for which purpose the pipes A and B are connected with an overhead, or gravity tank 16, 75 each of the pipes A and B, as clearly shown in Fig. 1 of the drawings, being extended beyond its distributing pipe 12, or 14, to connect with the tank 16, and the pipe A having a check valve 17 between its distributing 80 pipe, or pipes 12, and the tank 16, while the pipe B has a check valve 18 between its distributing pipe 14 and the pressure tank 16, which check valves open under pressure 85 from the tank 16, but close under pressure acting toward the tank 16. It will be seen that upon the opening of a sprinkler head, or other means of discharge of extinguishing fluid from either the pipe A, or the pipe B, 90 the level of the liquid in the tank 16 will fall because of the efflux of liquid from the open sprinkler head, or other means of discharge, and I utilize the dropping of the level of the liquid in the tank 16 to produce automatically the creation, or calling into action of 95 the desired pressure for forcing the extinguishing fluid, whether chemical or water, to and out of the open sprinkler head.

The tank 11, besides holding water, or some chemical other than the kind in tank 10, is made to serve as the receptacle in which the expelling pressure is generated. For this purpose I place and support within it a cup 19 which may be conveniently suspended from a hollow neck, or flange 20 depending from the cover 21, which closes the tank 11, and within the cup 19 is placed a can or holder 22 that contains a material 23,

which, upon contact with water 24 in the cup 19 results in the prompt evolution of a great volume of oxygen which escapes as fast as it is evolved through a hole 25 in the side of 5 the neck 20 that communicates with the upper part of the tank 11 and subjects the water or other liquid in the tank 11 to an expelling pressure which forces it through the pipe B and thence to any open sprinkler 10 head in the distributing pipe 14. The material I employ for the evolution of the oxygen, is sodium peroxid. Of course, the expelling pressure may be produced otherwise than by the use of this particular material, as, for example, by the use of the well known sulfuric acid and bi-carbonate of 15 soda.

Pressure from the tank 11 is delivered to the extinguisher-holding tank 10 by a pipe 20 26 that runs from the top of the tank 11 to the top of the tank 10, a check device 27 having the construction shown in detail in Fig. 4, being interposed between the two tanks for the purpose of preventing under 25 normal conditions the coming together of carbon tetra chlorid in the tank 10 and aqueous vapor from the water in the tank 11, which might result in the evolution of gas that would be injurious to the apparatus. Said check device 27 is in the nature 30 of a trap, as shown in Fig. 4, it having a depending chamber 28 into which projects a partial wall, or partition 29 that reaches close to the bottom of the chamber 28, dipping 35 at its lower end into a volume of mercury 30, which constitutes a seal that prevents communication on opposite sides of the partition 29. Under conditions of pressure in the tank 11, the mercury will be displaced and allow the pressure to enter and accumulate in the top of the tank 10 ready 40 to be restored back through the pipe 26 to the tank 11, when the pressure in the latter falls below that in the tank 10, as when 45 one of the sprinkler heads 15 is open and a discharge from it is taking place while all the sprinkler heads 13 in the distributing pipe 12 remain closed. Any pressure in the tank 10 tending to force liquid up through 50 the pipe A, will be opposed by the check valve 17.

Within the tank 16 is a float 31 carried by an arm 32 pivoted to the inner side of the tank, and, which, of course, moves vertically according to the level of the liquid 55 in the tank 16. The float arm 32 is connected by a section of chain 33, or other flexible agent, and a rod 34 with one end of a lever 35 whose other end is connected, as 60 by a chain 36 with a trigger 37 which normally engages and locks from movement a trip lever 38 from which is suspended a weight 39, which, upon the operation of the trigger 37 and the consequent release of the trip 38, descends, and through a lever 40,

with which it is connected and which has a gear segment 41 revolves a vertical shaft 42, the shaft 42 having a bevel pinion 43 which meshes with the gear segment 41. The shaft 42 passes through a hole in the tank cover 21 70 into the cup 19, and it has a threaded portion 44 which engages a thread 45 in the cover hole through which it passes so that by the revolution of the shaft 42 consequent upon the descent of the weight 75 39, the shaft 42 will descend. At its lower end the shaft 42 has a head 46 adapted to engage a plug 47 in the top of the container 23, and forces the same downward thus opening the otherwise closed top, and the 80 pressure transmitted through the body of material 23 is transmitted to a plug 48 in the bottom of said can, or container 22, and said plug 48 is expelled so that commingling 85 of the water in the cup 19 and the reagent in the can 22 may take place. The can 22 is supported sufficiently above the bottom of the cup 19 as to allow the expulsion of the bottom closing plug 48. Since the shaft 42 descends, as it revolves, the gear segment 90 41, has a spiral form so that it continues in mesh with the pinion 43 notwithstanding changes in the vertical position of the latter due to vertical movement of the shaft 42. A suitable packing 49 is provided 95 above and below the threaded portion 44 of the shaft 42 so as to assume a fluid-tight joint. The chain, or flexible connection 33 is provided between the float 31 and the trigger-operating lever 35 so that no movement of 100 the trigger will take place in consequence of such fluctuation of level of the liquid in the tank 16 as may take place from evaporation, or expansion, and it is only when a considerable fall in the level of the liquid 105 takes place, as when a sprinkler head opens, that the descent of the float 31 results in the rocking of the lever 35 to release the trigger 37. The tank 16 is preferably closed by a 110 cover to prevent evaporation, and a valve inlet 50 is provided in the cover to allow the ingress of air on the fall of the level of the liquid in the tank. The tank 16 in its horizontal dimensions is wide so that it is a shallow tank in order that any changes of 115 volume of liquid in the tank and the pipes connected therewith may result in but little change in the level of the liquid in the tank 16,—not enough to cause the automatic operation of the apparatus. If desired, as 120 shown in Fig. 3, an air dome, or reservoir 51 may be provided that is connected by a pipe 52 with the interior of the tank 16 and having within the latter a normally closed valve 53, which, upon the descent of the 125 float 31 to a predetermined point will be opened by the downward movement of the lever 54 connected with the valve and thereby air permitted to flow from the dome 51 into the tank 16 to supplement the action 130

of gravity in forcing the liquid through the tank 16.

In the form of my invention illustrated in Fig. 2, provision is made for the simultaneous delivery of the two different kinds of extinguishers, for example, carbon tetrachlorid and water at certain points in the system.

The apparatus is identical with that shown in Fig. 1, excepting that instead of having disconnected distributing pipes 12 and 14 they are connected, but with a check valve 55 interposed in the pipe between the series of sprinkler heads designated 15 and the series of sprinkler heads designated 13, and in this case the tank 11 contains the carbon tetrachlorid while the tank 10 contains water. Upon the opening of one of the sprinkler heads 15, it will be seen that the operation of the pressure-producing means in the tank 11, will be started and carbon tetrachlorid expelled from the open sprinkler head 15, and if later, or at the same time one of the sprinkler heads 13 opens, then water will be forced therefrom and the carbon tetrachlorid will pass through the check valve 55 to the sprinkler head 13 which is issuing water so that simultaneously water and carbon tetrachlorid will be applied to the fire, the carbon tetrachlorid acting primarily as an extinguisher and the water serving to wet down the embers, and the surroundings and prevent the fire starting up again. When only the sprinkler heads 15 are opened no water is discharged at any point because the check valve 55 prevents water flowing into the distributing pipe 14 which contains the sprinkler heads 15.

The flow of liquid through the distributing pipes to the sprinkler heads occurring upon the outbreak of the fire may be utilized to sound an alarm automatically, and for this purpose a valve 56 having the construction shown in Fig. 5 may be applied to the distributing pipes as indicated in Fig. 3. Said valve comprises a casing within which is pivoted a flap, or valve 57 adapted to be swung off its seat 58 by the flow of liquid through the distributing pipe and through a sliding rod 59 which passes from the interior of the valve casing to the outside is adapted to open a switch 60 in a normally closed circuit that includes a bell, or other form of alarm. To prevent the operation of the alarm by such fluctuation in the volume of the liquid in the pipes, as may take place under ordinary, or normal conditions, and assuring that it will operate only when there is some sudden and extensive change in the volume, as upon the outbreak of a fire, the flap, or valve 57 has a small hole 61 through which there may be a flow of liquid to the opposite sides of the flap 57 without moving the latter, and said hole 61 is adapted to be

closed by the valve 62 attached to the valve 57 on the side to which the valve 57 is subjected to pressure to open it, which supplemental valve 62 is yieldingly held off its seat by a light spring 63 so that upon the sudden rush of liquid consequent upon the opening of a sprinkler head, as in the case of fire, the valve 62 will close the hole 61 and full force of the liquid will act upon the valve 57 to move it off its seat and operate the circuit-closing device of the alarm mechanism.

The cup 19 containing the can, or package of reagent, may be supplied in the form of a cartridge, as shown in Fig. 6, so that it may most conveniently be placed within the pressure tank 11. All that is necessary to do in providing for use, under these circumstances, is to place a cap, or cover 64 on the threaded upper end of the cup 19, by which it is screwed to the neck 20 depending from the tank cover 21. Of course, this cover is removed at the time of placing of the cartridge in the tank and thrown away. The water in the cup 19 is rendered non-freezing by a suitable proportion of alcohol. For supplying liquid to the tank 16, when it is provided with a cover, the latter may be removed and then replaced, or a filling nozzle of well-known description may be provided.

Having thus described my invention what I claim is—

1. In fire extinguishing apparatus, the combination of a plurality of sources of extinguishers of different kinds, a separate distributing system connected with each source, each distributing system having a normally closed discharge means that automatically opens under fire conditions, a common means for supplying pressure to expel the extinguishers from all the sources when their respective discharge means open, and automatic means to control the supply of pressure connected in common with the several distributing systems and placed in condition to supply pressure when the normally closed discharge means of any one system opens.

2. As an improvement in fire extinguishing apparatus, the combination of a holder for a chemical extinguisher, a distributing pipe leading therefrom provided with a sprinkler-head, that automatically opens under fire conditions, a second extinguisher holder, a distributing pipe leading therefrom and provided with a sprinkler-head that automatically opens under fire conditions, means for generating pressure, means for supplying pressure from said generating means to one of said holders, means to transmit pressure from one holder to another; a normally inactive device for causing the operation of the pressure generating means, and automatic means connected with said device and with the distributing pipes of said holders, whereby upon the opening of a sprinkler head in any distributing pipe, said

device will be actuated to cause the generation of pressure.

3. In fire extinguishing apparatus, the combination of a plurality of mechanisms, each comprising a fire-extinguisher holder and a liquid-filled distributing pipe leading therefrom having normally closed automatically openable discharge orifices that open under fire conditions, a common means for supplying pressure to expel the contents of said holders into their respective distributing pipes, means for transmitting pressure from one holder to another, and a single means operably in communication with the liquid in said pipes for controlling said pressure supplying means, acting on the opening of any one of said discharge orifices.

4. In fire extinguishing apparatus, the combination of two sources of supply of fluid extinguishers of different kinds, a connection between such sources of supply, including a trap having a liquid seal, and means for supplying pressure to the fluid in said sources of supply to expel the fluid therefrom.

5. In fire extinguishing apparatus, the combination of a plurality of sources of extinguishers of different kinds, a plurality of normally closed discharge means one connected with each source, means for the generation of pressure by the action of reagents, common to the various sources, means for transmitting pressure to all said sources at the same time, and automatic means to control the action of the reagents connected

in common with the various discharge means, said automatic means acting upon the opening of any of said normally closed discharge means.

6. In a fire extinguishing apparatus, the combination of a plurality of tanks, a separate distributing pipe leading from each tank and provided with sprinkler heads, means within one of said tanks for the supply of pressure to expel the contents thereof, means connecting the tanks to transmit pressure from one to another, and automatic means to control said pressure-supplying means, in operative connection with each of the distributing pipes and acting on the opening of any sprinkler head.

7. In fire extinguishing apparatus, the combination of a plurality of tanks each containing a fire extinguishing fluid, a separate distributing pipe leading from the lower part of each tank, a separate discharge point for each distributing pipe, an automatically openable sprinkler head at each discharge point, means in one of said tanks for the generation of pressure by the action of reagents, means whereby reagents are brought together in said tank upon the opening of a sprinkler head, and a pipe leading from the upper part of one tank to the upper part of another tank for the transmission of pressure from one tank to another for the expulsion of extinguishing fluid.

In testimony that I claim the foregoing I have hereunto set my hand.

EDWARD R. BRODTON.
